INVENTOR.

William D. Seddon
BY John T. Kerr
ATTORNEY.

UNITED STATES PATENT OFFICE.

WILLIAM D. SEDDON, OF PATERSON, NEW JERSEY.

DIAMOND-CUTTING.

SPECIFICATION forming part of Letters Patent No. 712,155, dated October 28, 1902.

Application filed April 2, 1902. Serial No. 101,138. (No model.)

To all whom it may concern:

Be it known that I, WILLIAM D. SEDDON, a citizen of the United States of America, and a resident of Paterson, in the State of New Jersey, have invented a new and useful Improvement in Diamond-Cutting, of which the following is a specification, reference being had therein to the accompanying drawings, which form a part thereof.

10 The invention relates to the cutting of diamonds or other precious stones; and it consists, essentially, in cutting the upper and lower surfaces to form peculiarly-shaped facets, as will be hereinafter fully described, and particularly set forth in the claims.

15 The principal object of the invention is to enhance the brilliancy of precious stones, more especially diamonds, to intensify the prismatic hues, and to increase the receptive 20 and reflective surface by incisive or what may be termed "inside" cutting.

In the drawings, Figure 1 is a top view of the diamond according to my invention; Fig. 2, a side elevation; Fig. 3 a view of the bottom; and Fig. 4 is a vertical section taken along the valley-line *c*, showing the formation of the valley.

25 Referring to Figs. 1 and 2, it will be seen that the table or top of the upper part of the stone is formed of horizontal ridges or edges *b b*, which meet and intersect at the center in the same horizontal plane, having sloping triangular sides or facets *a a a*, radiating from the center, forming the valleys *c c* between them, said valleys sloping from the center toward the girdle. These prismatic facets are 30 surrounded by a series of pentagonal and triangular facets *d d d* and *e e e*, forming the bezel and reaching to the girdle of the stone.

35 40 The lower or under side of the stone, as shown in Figs. 2 and 3, has a deeply-cut set of valleys between ridges, forming sloping triangular facets at the extremity in lieu of the apex or culex of the inverted polygonal pyramid which forms the bottom of the common brilliant cutting, and in this lower prismatic table the ridges or edges *f f* meet and intersect at the center in the same horizontal plane and have sloping triangular sides or facets *g g*, radiating from the center, and the valleys *k k* between them, that slope from the center toward the girdle. These facets are

surrounded by a series of pentagonal facets *h h h*, that form the sides of the inverted truncated cone, and a series of triangular facets *i i i*, reaching to the girdle, which is the base of the truncated cone.

55 My improvement, as will be seen, cuts the stone in such a manner that each central extremity of the upper and lower sides is fashioned into triangular sloping facets, forming triangular prisms radiating from the center instead of being a central point, culex, or table.

60 The number of horizontal intersecting ridges on the top or bottom of the stone may be increased without departing from the scope and spirit of my invention.

Having thus fully described my invention, what I claim as new, and desire to secure by Letters Patent, is—

1. As an article of manufacture, a diamond, or other precious stone, the table or top of which consists of ridges *b b*, lying in a common horizontal plane intersecting at a common center, and having sloping triangular sides or facets, *a a a*, radiating from the center, forming between them the sunken portions or valleys, *c c*, which slope from the center toward the girdle, and a series of pentagonal and triangular facets, *d d d*, and *e e e*, respectively surrounding the facets *a a a*, forming the bezel and reaching to the girdle of the stone, substantially as set forth.

75 80 2. As an article of manufacture, a diamond, or other precious stone, having its top or upper face suitably cut and its bottom or lower face at the central extremity consisting of ridges *f f*, in the same horizontal plane and intersecting at the center, and which have sloping triangular sides or facets *g g*, radiating from the center, forming between them the sunken portions or valleys *k k*, that incline from the center toward the girdle, and a series of oblong pentagonal facets, *h h h*, and 90 a series of triangular facets, *i i i*, respectively surrounding the facets *g g* and reaching to the girdle, substantially as specified.

95 100 3. As an article of manufacture, a diamond or other precious stone, the table or top of which consists of edges or ridges in the same horizontal plane intersecting at the center and which have sloping triangular sides or facets, radiating from the center, forming be-

tween them sunken portions or valleys that slope from the center toward the girdle, and a series of pentagonal and triangular facets surrounding the said facets forming the bezel and extending to the girdle, and its bottom or lower face at the central extremity consisting of edges or ridges in the same horizontal plane and intersecting at the center, and which have sloping triangular sides or facets, radiating from the center, forming between them sunken portions or valleys, that incline

from the center toward the girdle, and a series of oblong pentagonal facets and a series of triangular facets respectively surrounding the said facets and extending to the girdle. 15

In testimony whereof I affix my signature in presence of two witnesses.

WILLIAM D. SEDDON.
